US00D499721S

(12) **United States Design Patent** (10) Patent No.: **US D499,721 S**
 Leith et al. (45) Date of Patent: **** Dec. 14, 2004**

(54) **KEY BUTTON ARRANGEMENT FOR A HANDSET**

(75) Inventors: **Daren Leith**, Hampshire (GB); **Iain Pottie**, Berkshire (GB); **Anthony Dalby**, London (GB)

(73) Assignee: **Nokia Corporation**, Espoo (FI)

(**) Term: **14 Years**

(21) Appl. No.: **29/186,387**

(22) Filed: **Jul. 16, 2003**

(30) **Foreign Application Priority Data**

Feb. 7, 2003 (FI) M20030049

(51) LOC (7) Cl. **14-03**

(52) U.S. Cl. **D14/247**

(57) **CLAIM**

The ornamental design for a key button arrangement for a handset, as shown and described.

DESCRIPTION

FIG. 1 is a front view of a key button arrangement for a handset showing our new design; and,
 FIG. 2 is a perspective view thereof.

The uneven broken line showing of the remainder of the handset in FIGS. 1-2 is for illustrative purposes only and forms no part of the claimed design.

1 Claim, 2 Drawing Sheets

FIG. 1

FIG. 2
